United States Patent Office.

E. R. HALL, OF SYRACUSE, NEW YORK, ASSIGNOR TO HIMSELF, WILLIAM H. TOWN, AND CHARLES E. CANDEE, OF SAME PLACE.

Letters Patent No. 91,121, dated June 8, 1869.

IMPROVEMENT IN SAWING-MACHINES.

The Schedule referred to in these Letters Patent and making part of the same.

To all whom it may concern:

Be it known that I, E. R. HALL, of Syracuse, in the county of Onondaga, and State of New York, have invented a new and valuable Improvement in Wood-Sawing Machines and Churn Combined; and I do hereby declare that the following is a full, clear, and exact description of the construction and operation of the same, reference being had to the annexed drawings, making a part of this specification, and to the letters and figures of reference marked thereon.

Figure 1, of the drawings, is a top plan view of my device.

Figure 2 is a longitudinal sectional view of the same.

Figure 3 are details.

My invention relates to wood-sawing machines; and it consists, mainly, in the construction and novel combination of devices, by which the wood is raised to the saw automatically by the same motive-power that moves the saws.

It also consists in combining with the sawing-apparatus novel devices by which a churn-dasher may be operated vertically.

The letter A of the drawings represents the sides of my frame, united by suitable cross-beams.

The letter B represents the saw-horse, arranged between the posts a, and resting upon the châius c, as shown.

The letter d represents the saws arranged in the gate e, which is arranged to move horizontally by means of cranks and grooves, as is usual with this class of wood-saws.

The letter f is a bar, arranged as shown, to which the rear ends of the chains c are attached, and

The letter g is a roller, over which said chains are passed on the opposite side of the saw-buck from the bar f.

The letter h is a ratchet-bar, attached to the rear side of the saw-buck, and

Letter i is a pawl-lever working thereon.

This lever i is pivoted to the lower side of the rear part of the saw-buck, and

Letter l is a chain, attached to said lever. Said chain is fastened, at its opposite end, to the front side of the saw-buck.

The function of this chain, ratchet, and pawl-lever is to hold the log securely upon said saw-buck. The chain is passed over the log, and the lever is pressed down until the chain is sufficiently tightened, when it is made secure by placing the lever under one of the teeth of the ratchet.

The letters m are rollers under the buck, and attached thereto, as shown.

The chains c extend from the beam or bar f to the shaft n, to which they are firmly affixed, as represented.

When the saw-buck is to be raised, the shaft n is

rotated. This action serves to wind the chain around the shaft, and the buck is raised.

The method I have adopted for actuating this shaft n is by attaching a pinion to one end thereof, which meshes with a pinion on the working-shaft of the machine, and adjusting its front bearing in the side of a movable lever, in such manner that the pinions of the shaft may be thrown in or out of gear at will.

The working shaft above referred to is represented by the letter o, and the movable lever is shown by the letter p on the drawings.

When the pinions are in gear, I insert a wedge in the slot of the frame, through which the lever p is passed, on the rear side of said lever, and thus keep the pinions in gear as long as is desirable.

To throw the pinions out of gear, I remove the wedge, when they immediately separate.

The letter D is a large cogged wheel, attached to the end of the working-shaft, and

Letters E and F are pinions working therewith, as shown.

I usually apply the power to a drum, attached to pinion E in the ordinary manner.

The shaft to which the pinion F is attached is marked G on the drawings. It has cranks of the usual form inside the frame, to which the pitmen of the saw-frame are attached, and worked in the usual way. These pitmen are marked r on the drawings.

My device for actuating a churn-dasher is as follows:

I pivot two arms, marked s, to the pitmen, and unite their tops, by hinges or pivots, to horizontal arms, marked t.

The arms t are attached to a shaft, u, which rests and works in bearings formed in the top of the upright standards v, which standards are affixed to the frame in the manner shown.

Another arm, marked w, extends forward from the shaft u, to the end of which I pivot a rod, y.

The letter a' is a spirally-grooved rod, united by a swivel-head with the rod y, and adapted for union with a churn-dasher by slot and pin.

This rod a' operates in a suitable opening in the guide b', which is arranged inside, and extends to the front of the standards v, as shown.

In the openings formed in said guide, I arrange suitable pins, that work in the groove of the rod a', and secure for it a rotary movement.

The letter H represents a churn, in which the dasher operates.

The device shown on the left-hand figure of fig. 3 is intended for use in removing the rear end of the saw-frame from its grooves in the frame of the machine. It consists of two sliding arms, separated by a spiral spring, the ends of which arms pass into the grooves of the frame. These bars work in grooves in the head-

block of the same, and the object I accomplish is to draw these arms from their grooves inward at will, and thereby release the saw-frame from the frame of the machine. These arms are marked *c*', and the spring is marked *d*'.

The letters *e*' are removable arms, affixed to the sides of an upright block, extending upward from the head-block of the saw-frame, and are arranged to move up and down on the sides thereof at will.

They are pivoted to the sides of the block *f*', which in turn is pivoted to the top of the horizontal bar of the frame, in the manner represented in fig. 2.

By pressing downward upon the block *f*', the arms *e* are forced against the bevelled flanches of the arms *c*', thereby pressing said arms inward, and releasing their outer ends from their respective grooves.

What I claim as my invention, and desire to secure by Letters Patent, is—

1. The chains *c*, rollers *g* and *m*, shaft *n*, lever *p*, and pinions on the working-shaft, and shaft *u*, as described, when constructed and arranged substantially as and for the purpose specified.

2. The arms *s*, *t*, and *w*, shaft *u*, rods *y* and *a*', and guide *b*, when all the parts are constructed, arranged, and operating substantially as and for the purposes specified.

3. The arms *c*' and *e*, spring *d*', and hinged block *f*, when constructed, arranged, and operating substantially as and for the purposes herein specified.

In testimony that I claim the above, I have hereunto subscribed my name, in the presence of two witnesses.

E. R. HALL.
